VALVE CONSTRUCTION

Paul F. Berry, Columbus, Ohio

Application October 27, 1932, Serial No. 639,904
Renewed June 18, 1935

4 Claims. (Cl. 230—222)

This invention relates to a valve construction, and it is an object of the invention to provide a construction of this kind comprising two relatively movable rock members operating in required sequence one with respect to the other to allow for the desired intake or exhaust of a fluid.

It is also an object of the invention to provide a structure of this kind which is particularly applicable for use in connection with small units such as the compressor units of refrigerating apparatus.

Another object of the invention is to provide a valve construction of this kind for use in connection with a compression cylinder or the like and which construction operates in a manner to assure substantially full effective strokes of the piston reciprocating within the cylinder and more particularly the suction stroke of the piston.

The invention consists in the details of construction and in the combination and arrangement of the several parts of my improved valve construction whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

Figure 1 is a fragmentary view partly in vertical section and partly in elevation showing a valve constructed in accordance with my invention and in applied position in connection with a compressor;

Figure 2 is a view partly in section and partly in side elevation of one of the valve members as herein embodied together with the associated operating means therefor, certain of the ports comprised in the valve structure being indicated by broken lines;

Figure 3 is a fragmentary view partly in elevation and partly in section illustrating the valve members in position for intake into the compression cylinder;

Figure 4 is a view in plan of the face of one of the valve members coacting directly with the compression cylinder;

Figure 5 is a view in elevation of the inner face of the second valve member.

As disclosed in the accompanying drawing, I denotes a drive shaft upon which is mounted for rotation therewith a disc 2 provided in each of

its side faces with the cam groove 3, said cam grooves being of similar formation but in reverse relation. One of the grooves 3 is indicated by full lines in Figure 2 and the other by broken lines in such figure.

The shaft 1 also operates to actuate a compressor piston 4 operating in a cylinder 5. The wall 6 separating the cylinder 5 and the suction chamber C is formed with a flat face 7 against which operates one of the rocking or oscillating valve members 8. With the outer face of the valve member 8 contacts a second rocking or oscillating valve member 9. These members 8 and 9 are mounted for rocking or oscillating movement about a common axis and herein disclosed as a pin 10 bridging the space between the flat face 7 of the wall 6 and the block 11. The block 11 is slidably mounted within the cylindrical guide sleeve 12 extending within the chamber C through the outer wall 14 thereof. This block 11 is chambered, as at 15, and is provided with a port 16 for coaction with a port 17 disposed through the valve member 9. The outer end of the chamber 15 communicates with the interior of a bellows-like metal structure 18 which is sealed or otherwise effectively connected to the block 11 at its inner end and at its outer end is sealed or otherwise effectively connected to a plate 19 closing the outer end of the opening 20 through the wall 14 through which the guide sleeve 12 is directed. This plate 19 has connected thereto a discharge line 21 for communication with the interior of a condenser (not shown) and after the fashion shown in Patent #1,799,449 dated April 7, 1931 and with which type of refrigerating apparatus the valve construction as herein disclosed is particularly intended to be used.

The pressure generated within the bellows-like structure 18 will cause the same to expand 40 forcing the block 11 against the valve member 9, the valve member 9 against the valve member 8, and the valve member 8 against the flat face 7 thus assuring a perfect seal.

The valve member 8 is provided therethrough 45 with a port 22 for register with the port 17 and which port 22 is also adapted to be brought into register with a port 23 extending through the wall 6 and opening into the cylinder 5 inwardly at all times of the piston 4 working therewith. The face of the valve member 8 which contacts with the flat face 7 of the wall 6 is provided with a channel or groove 24 intersecting the port 22 and which is adapted to afford communication with the port 23 when the port 22 50 55

of the member 8 is to one side of said port 23. The port 22 is also adapted to register with a radially disposed groove or channel 25 provided in the inner face of the valve member 9 and opening through the periphery of said valve member 9.

The registration of the port 22 with the groove or channel 25 occurs when the port 22 has been moved a predetermined distance to one side of the port 23 and during which time the groove or channel 24 is in communication with the port 23 so that upon the suction stroke of the piston 4 the gas and/or vapor within the chamber C will be drawn into the cylinder 5 through the groove or channel 25, the port 22, the groove or channel 24 and the port 23. During this operation the valve members 8 and 9 will be in the position as illustrated in Figure 3 to bring the ports 22 and 17 out of register.

When the ports 17 and 22 are in register the gas and/or vapor compressed within the cylinder 5 will pass out directly through the ports 23, 17 and 22 and through the port 16 to the line 21.

Overlying the side faces of the disc 2 are the arms 26 and 26' each of which having a part 27 as indicated by broken lines in Figures 1 and 2 riding in the cam groove 3 of the adjacent side face of the disc 2. These arms 26 and 26' are disposed on such angle to assure the desired rocking movement of the arms in proper sequence as determined by the grooves 3. These arms 26 and 26', as herein disclosed, are suspended for rocking movement from a pin 28 supported at a desired point above the disc 2 and the mounted extremities of the arms 26 and 26' are continued by the arms 29 and 29' each having requisite operative connection, as at 30, with one of the valve members 8 or 9.

In the operation of a refrigerating apparatus and especially of the type as particularly disclosed in Patent #1,799,449 hereinbefore referred to, oil evaporated in the course of operation of the machine will become intermingled with the gas drawn into the suction chamber C and with the groove or channel 25 in register with the port 22 and the passageway 24 in communication with the port 23, the gas and oil vapor will pass into the cylinder 5 upon the intake stroke of the piston 4. When the piston 4 has substantially reached the end of its intake stroke, the cam grooves 3 will effect through the arms 26 and 26' a reverse movement of the arms 29 and 29' also resulting in a reverse rocking movement of the valve members 8 and 9 to the positions illustrated in Figure 3 and in which positions the valve members 8 and 9 effectively seal against flow through the port 23.

Upon the rising or reverse stroke of the cylinder 5 the gas and/or vapor within the cylinder will be compressed and this compression action will take place until the piston 4 has substantially completed its compression stroke whereupon the cam grooves 3 will effect a reverse rocking movement of the valve members 8 and 9 to bring the ports 17 and 22 in register with each other and with the port 23 whereupon the compressed gas will pass out through said ports 23, 22 and 17 to the chamber 15 and from thence through the bellows-like structure 18 and line 21 to the condenser.

From the foregoing it is believed to be clearly understood that the operation of the valve members 8 and 9 assure an effective functioning of

the piston 4 throughout substantially the entire length of each of its cycles.

From the foregoing description it is thought to be obvious that a valve construction constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed. 15

I claim:—

1. In a pump, in combination, a pair of rock valves arranged side by side and a seat for one of the valves, said seat having a port, means for axially supporting the valves, elastic means for urging the valves one toward the other and toward the valve seat, means for reversely rocking the valves in timed sequence, said valves having ports in register with each other and with the port of the valve seat upon rocking movement of the valves in one direction, said ports being out of register upon movement of the valves in their opposite directions whereby flow through said ports is closed, one of said valves having a passageway registering with the port of the valve seat when the ports of the valves are out of register, said passageway also communicating with the port of the second valve when the ports in both of the valves are out of register, and an inlet passageway carried by said second valve registering with the port of the first valve when the ports of both valves are out of register. 35

2. A pump comprising, in combination, a pair of valve members arranged side by side, a seat for one of the valve members, an axial support for the valve members, said valve members having movement along said support, said seat having a port and each of the valve members having a port therethrough, the ports of the valve members being adapted to register with each other and the port of the valve seat, means for rocking said valve members one with respect to the other to position the port of one of the valve members to one side of the port of the second valve member whereby flow is closed through the valve members, opposed portions of the valve members having passageways in communication with each other and with the port of the valve seat and the port of one of the valve members when said valve members are in a position to close flow therethrough, means for rocking the valve members in timed sequence, and means for urging the valve members toward the valve seat. 50

3. A pump comprising, in combination, a pair of valve members arranged side by side, a seat for one of the valve members, an axial support for the valve members, said valve members having movement along said support, said seat having a port and each of the valve members having a port therethrough, the ports of the valve members being adapted to register with each other and the port of the valve seat, means for rocking said valve members one with respect to the other to position the port of one of the valve members to one side of the port of the second valve member whereby flow is closed through the valve members, opposed portions of the valve members having passageways in communication with each other and with the port of the valve seat and the port of one of the valve members when said valve members are in a position to close flow 70

bers are in a position to close flow therethrough, means for rocking the valve members in timed sequence, and elastic means for urging the valve members toward the valve seat.

- 5 4. A pump comprising, in combination, a pair of valve members arranged side by side, a seat for one of the valve members, an axial support for the valve members, said valve members having movement along said support, said seat having a port and each of the valve members having a port therethrough, the ports of the valve members being adapted to register with each other and the port of the valve seat, means for rocking said valve members one with respect to the other to
- 10 position the port of one of the valve members to one side of the port of the second valve member whereby flow is closed through the valve members, opposed portions of the valve members having passageways in communication with each other and with the port of the valve seat and the port of one of the valve members when said valve members are in a position to close flow therethrough, means for rocking the valve members in timed sequence, and means for urging the valve members toward the valve seat, the movement of the valve members being in reversed directions.

PAUL F. BERRY.
